HENRY E. VAN NESS, OF ELMIRA, NEW YORK.

YARN CLEANER.

Application filed June 8, 1922. Serial No. 568,722.

To all whom it may concern:

Be it known that I, HENRY E. VAN NESS, a citizen of the United States, residing at Elmira, in the county of Chemung and State of New York, have invented certain new and useful Improvements in Yarn Cleaners, fully described and represented in the following specification and the accompanying drawings, forming a part of the same.

This invention relates to yarn cleaners for eliminating from yarn impurities such as parts of seeds, parts of stems, slubs, specks, grains of sand, and other particles before the yarn is made into cloth, and thus improving the quality of the cloth made from the yarn and avoiding the necessity for excessive bleaching of the cloth.

An object of the invention is to provide a device adapted thoroughly to clean a traveling yarn without retarding the travel of the yarn, so that danger of breaking of the yarn in the cleaner is eliminated.

A further object of the invention is to provide a yarn cleaner adapted to discharge the particles removed from the yarn, without the use of any mechanically-driven parts.

Other objects and advantages of the invention are hereinafter pointed out in connection with a detailed description of a specific embodiment of the invention.

A yarn cleaner embodying the invention and adapted to accomplish the objects above outlined may include a frame provided with a plurality of resiliently supported elements which are set into vibration by the travel of the yarn, and which, when vibrating, serve to detach particles from the traveling yarn, and to direct the detached particles away from the line of the travel of the yarn and out of the cleaner. The vibratory elements may be of two forms, one form being adapted principally to loosen and detach particles from the yarn and the other form being adapted both to detach particles from the yarn and to direct detached particles away from the line of travel of the yarn and out of the cleaner. The vibratory elements are most desirably arranged so that they all operate upon a yarn traveling in a straight line, and the frame may be provided with a cover which insures bringing the yarn into operative relation with all the elements when the cleaner is threaded.

In order that the invention may clearly

be understood, I will describe in detail a yarn cleaner embodying the invention which is illustrated in the accompanying drawings, in which:—

Fig. 1 is a top view of the cleaner with the cover removed;

Fig. 2 is a side view sectioned on the line 2—2 of Fig. 1;

Fig. 3 is an end elevation on a larger scale, sectioned on the line 3—3 of Fig. 1;

Fig. 4 is a fragmentary plan view on a still larger scale, omitting the cover, and showing the operative portions of some of the vibratory elements;

Fig. 5 is an enlarged fragmentary vertical section on the line 5—5 of Fig. 3 showing the manner in which the vibratory elements are mounted in the frame;

Fig. 6 is an enlarged perspective view of one of the vibratory cleaning and deflecting elements;

Fig. 7 is an enlarged perspective view of one of the vibratory cleaning elements;

Fig. 8 is a fragmentary perspective view of one of the vibratory cleaning elements looking toward the cleaning edge, on a still larger scale; and

Fig. 9 is a fragmentary back view of a pair of cleaning and deflecting blades of modified construction.

The cleaner shown in the drawings is adapted to operate upon a traveling yarn which is being drawn from a bobbin or other supply into a winding or spooling or other machine. The cleaner may conveniently be secured to a portion of the frame of any such machine, and for this purpose there may be secured to the frame 10 of the cleaner a stud 11 containing a hole and provided with a set screw 12. It will be understood, however, that the cleaner may be mounted in any desired manner and will operate upon any traveling yarn regardless of the nature of the machine into which the yarn is being drawn.

The frame 10 of the cleaner may be rectangular and the ends 13 and 14 of the frame may conveniently be made integral with one side 15 of the frame. For a reason herein-after explained, it is desirable to form the other side 16 of the frame of a separate piece of metal and to attach it to the ends 13, 14 in such manner that the distance between it and the side 15 of the frame may be varied. In the form shown, the side 16 has a dovetail connection with the ends 13, 14 and is

secured thereto by means of screws 17 which have a threaded connection with the ends of the frame and pass through transverse slots 18 in the side 16, so that by loosening 5 the screws the side 16 may be moved slightly toward or away from the side 15 of the frame.

The ends 13 and 14 of the frame 10 are provided at their middles with recesses 20, 10 21 which permit a yarn A to be drawn longitudinally across the middle of the frame some distance below the upper edge of the frame.

To the end 13 of the frame, which I term 15 the front end because it is the end from which the traveling yarn enters the cleaner, is attached a tension device 19 which retains the yarn under tension as it is drawn across the frame of the cleaner. The tension device illustrated comprises a plate 19^a 20 which is secured to the end 13 of the cleaner and which has at its outer or front end an entrance recess 19^b. The portions of the plate 19^a at each side of the recess 19^b may 25 be turned up to form ears 19^c. The recess 19^b is in line with the recesses 20, 21 in the ends 13, 14 of the frame. On the plate 19^a 30 at one side of the center line of the recesses is mounted a vertical stud 19^d having a cylindrical shank and a non-circular head 19^e. On the plate 19^a and about the shank is seated an upper rotary tension member 19^f 35 which has a disc-shaped bottom 19^g and a wide flaring flange 19^h extending outwardly and upwardly from the periphery of the bottom. The flange 19^h extends above the top of the end 13 of the frame 10 and over the inner end of the entrance recess 19^b. One or more weight discs 19ⁱ having non- 40 circular holes fitting over the head of the stud may be seated on the bottom 19^g of the rotary tension member 19^f.

As the tension device illustrated forms a part of the subject matter of my copending 45 application, filed July 20, 1922, Serial No. 576,249, which is a continuation in part of the present application, the tension device is not claimed in the present application.

Beyond the rear end 14 of the frame 10, 50 and mounted either upon the rear end or upon a portion of the machine to which the frame is secured, is a yarn guide 19^j located below the bottom of the recess 21. The yarn which is drawn across the frame is 55 passed under the guide 19^j before it is led into the winding or other machine which causes its travel.

At the top of each of the sides 15 and 16 of the frame are long recesses 23, 22 which 60 provide space for the mountings of the vibratory elements which are hereinafter described.

The top of the frame 10 is closed by a cover consisting of two pieces 26, 27 whose 65 inner edges are spaced to provide a slot 28

adapted to permit the yarn to be drawn into the position indicated by dotted lines in Figs. 1 and 2. The cover pieces 26 and 27 are secured to the frame by means of screws 25 entering holes 31 in the ends of 70 the frame and projections 29, 30 on the sides 15, 16 of the frame between the recesses 23 and the recesses 22.

A skirt 32 extends downwardly from the frame to confine the particles and any matter removed from the yarn by the cleaner. The skirt 32 may conveniently be formed of a single piece of metal and secured to the ends 13, 14 and the side 15 of the frame by screws 33. The skirt 32 is not attached to 80 the side 16 of the frame, and the skirt is of sufficient width to allow for the adjustment of the side 16 which is provided by the slots 18.

Mounted on the sides 15, 16 of the frame 85 and extending inwardly therefrom are vibratory elements which serve to clean the yarn and to direct the matter removed from the yarn out of the cleaner. Two types of vibratory elements are shown in the drawings. The elements 50, 50' of the first type serve to loosen particles projecting from the yarn and to detach some of the particles from the yarn. As their principal function is to clean, these elements are hereinafter 90 termed "cleaning elements." The elements 70, 70' of the second type serve both to detach particles from the yarn and to deflect the detached particles away from the line of travel of the yarn and out of the 100 cleaner. Because of the two functions which they perform, these elements are hereinafter termed "cleaning and deflecting elements".

Two pairs of vibratory cleaning elements 50, 50' are shown in the drawings, and these 105 elements are located near the front end of the frame. Each cleaning element may conveniently be formed from a single piece of sheet metal as shown. The thickness of the sheet metal is somewhat exaggerated in 110 the drawings for the sake of clearness.

Each vibratory cleaning element 50 comprises a cleaning blade 53 and a resilient support 52. The outer end portion 54 of the support 52 is set in a transverse slot 51 extending downwardly from the bottom of one of the recesses 23 in the side 15 of the frame. The support 52 extends inwardly from the side 15 of the frame and is inclined toward the back end 14 of the frame. 115 The blade 53 extends inwardly from the inner end of the support 52 and is inclined toward the front end 13 of the frame. The inclinations of the support 52 and the blade 53 are such that the inner end of the blade 120 53 is substantially in line with the outer end portion 54 of the support 52.

The outer end portion 54 of the support 52 is held in its slot 51 by means of a washer 55 which is forced down by a screw 56 (see 130

Fig. 5). The recesses 23 in the side 15 of the frame provide space for the washers and the heads of the screws 56 below the lower surface of the cover piece 26.

5 In the end of the cleaning blade 53 of each element 50 is a semi-circular notch 57 extending parallel to the sides of the frame. For convenience in threading, the upper portion 58 of the end above the notch 57 is also made parallel to the sides of the frame and is rounded off at its upper corner 59. In the form illustrated the lower portion 60 of the end below the notch 57 is also made parallel to the sides of the 15 frame. The surface of the notch 57 and the front surface 61 of the blade 53 intersect in an acute edge 62, which I term the cleaning edge.

The cleaning elements 50' which are 20 mounted on the side 16 of the frame are similar in form to the cleaning elements 50, and in the drawings the parts of the elements 50' are designated by the same numerals as the corresponding parts of the 25 elements 50, a prime being added to each numeral.

The cleaning elements 50, 50' are arranged in the frame in staggered relation as illustrated. The inner ends of the elements 50 lie in a common vertical plane and the notches 57 are aligned. The inner ends of the elements 50' lie in a common vertical plane and the notches 57' are aligned. The lower corners of both sets of notches are 35 substantially on a level with the bottoms of the recesses 20, 21 in the ends 13, 14 of frame 10. When the cleaner is adjusted for cleaning yarns of diameters substantially equal to that of the notches 57, 57', the 40 distance between the sides 15 and 16 of the frame 10 is adjusted so that the planes in which the inner ends of the cleaning elements 50 and 50' lie are coincident and the centers of the notches 57, 57' lie on a straight 45 line, which is the line of travel of the yarn A through the cleaner.

The notches 57 and the cleaning edges 62 of the elements 50 surround one-half of the circumference of the yarn A, while notches 57' and the cleaning edges 62' of the elements 50' surround the other half of the circumference of the yarn. Each cleaning element is free to vibrate through the bending of its resilient portion 52. When the 55 elements are in vibration, the center point of the cleaning edge of each element moves in a plane including the line of travel of the yarn and in a curve tangential to the yarn. Consequently, the movement of each cleaning edge is substantially longitudinal of the yarn, having a relatively large component longitudinal of the yarn and a relatively small component away from the line of travel of the yarn.

65 The vibratory cleaning and deflecting ele-

ments 70, 70' are located in the portion of the frame to the rear of the cleaning elements 50, 50' except that one pair of the cleaning and deflecting elements is located between the two pairs of cleaning elements. 70 Each cleaning and deflecting element may conveniently be formed from a single piece of sheet metal as shown. The thickness of the sheet material is somewhat exaggerated in the drawings for the sake of clearness. 75

Each cleaning and deflecting element 70 comprises a blade 73 and a resilient support 72. The outer end portion 74 of the resilient support 72 is set in a transverse slot 71 in the side 15 in the same manner that 80 the supports of the cleaning elements 50 are set in the slots 51. The resilient support 72 extends straight inward from the side 15 of the frame, while the blade 73 extends transversely to the line of travel of the yarn 85 and is inclined rearwardly from the vertical at an angle of about 35°. The blade has a straight inner edge 75, which is perpendicular to the resilient support 72, and is inclined to the line of travel of the yarn by 90 reason of the inclination of the blade. The outer end portion 74 of the support 72 which is seated in the slot 71 is offset downward from the remainder of the support so that the top of the blade 73 is some distance 95 above the bottom of the recesses 20, 21, and lies close to the lower surface of the cover piece 26. A slight clearance is allowed, however, to leave the element free to vibrate. To facilitate threading, the upper corner 100 of the inner edge 75 of the blade 73 is rounded off at 79.

The cleaning and deflecting elements 70' are similar to the elements 70, except that each of them has at its inner edge 75', some distance below the upper end of this edge, a semi-elliptical notch 80 extending 105 parallel to the sides of the frame.

The cleaning and deflecting elements 70, 70' are arranged in the frame in pairs, each 110 of the elements 70' being directly opposite one of the elements 70. The inner edges 75 of the elements 70 lie in a common vertical plane positioned slightly to one side of the center line of the frame. The inner edges 115 75' of the elements 70 lie in a common vertical plane substantially at the center of the frame, and the notches 80 in these edges are aligned with each other and with the notches 57' of the elements 50'. When the 120 cleaner is adjusted for cleaning yarns of diameters substantially equal to that of the notches 80, the distance between the sides 15 and 16 of the frame 10 is adjusted so that the planes in which the inner edges 75, 75' 125 of the cleaning elements 70, 70' lie are separated by a distance equal to half the diameter of the yarn. Consequently, the notches 80 of the blades 73' surround one-half the circumference of the yarn A, while 130

the inner edges 75 of the blades 73 lie adjacent to the other side of the yarn.

Each of the cleaning and deflecting elements 70, 70' is free to vibrate through the bending of its resilient support 72 or 72'. The bending of each resilient support 72 or 72' occurs principally at the part of the support just inside the side of the frame. This is because the greatest bending strain occurs at this point and also because the outer end portions 74, 74' of the supports are preferably made a little narrower than the remainder of the supports, as seen in Figs. 3 and 6. Consequently, when the inner edge of one of the blades 73, 73' is struck by a particle projecting from the yarn, the blade turns outwardly substantially about a vertical axis lying at the inner end of the slot 71 in which its support 72 is mounted. In such turning the upper end of the edge 75 or 75' of the blade moves in a curve tangential to the center line of the frame, while the portion of the inner edge adjacent to the yarn moves substantially in a curve tangential to the yarn. Since, however, each of the blades 73, 73' is inclined to the vertical axis about which it turns, the lower end of its inner edge 75 or 75' moves outwardly to a greater extent than the upper portion of its inner edge. As a result, when one or both of the resilient supports 72, 72' of a pair of elements 70, 70' are bent rearwardly, the inner edges 75, 75' of the blades 73, 73', instead of lying parallel to each other as in their normal position, diverge from each other toward their lower ends.

A plurality of pins 90 extend inwardly from the side 16 of the frame. The upper surfaces of these pins lie in a horizontal plane tangential to the notches 57, 57' and the notches 80 at their lower corners, so that the pins aid in placing the yarn in operative relation to the notches when the cleaner is threaded and serve to prevent the yarn from dropping below the notches in case the yarn is slackened.

The use of the cleaner is as follows:—

The cleaner is first adjusted in accordance with the diameter of the yarn in connection with which it is to be used. The adjustment is effected by loosening the screws 17 and moving the side 16 of the frame slightly inwardly or outwardly. If the diameter of the yarn is substantially equal to that of the notches 57, 57' and 80, the side 16 is positioned as shown in the drawing so as to bring the centers of the notches 57' on a line with the centers of the notches 57 and to make the distance between the inner edges 75' of the elements 70' and the inner edges 75 of the elements 70 equal to one-half the diameter of the yarn. Owing to the compressibility of the yarn, yarns whose diameters vary somewhat from

that of the notches 57, 57' and 80 may be successfully cleaned with the device adjusted as illustrated. If, however, the diameter of the yarn is materially different from that of the notches, the cleaner should be adjusted so that the notches 57, 57' surround the yarn as closely as possible, while at the same time the distance from the middle of each notch 80 to the edge 75 opposite is made substantially equal to the diameter of the yarn. This is done by moving the side 16 of the frame slightly inwardly if a smaller yarn is to be cleaned, or slightly outwardly if a larger yarn is to be cleaned.

The cleaner and its tension device are threaded by drawing the yarn into the entrance recess 19^b across the top of the rotary tension member 19^c into the slot 28 between the cover pieces 26 and 27 and the recess 21 in the end 14. The yarn is then passed under the guide 19^d and drawn forward by a winding or other machine not shown in the drawings. As soon as the pull is applied to the yarn by the winding machine, the yarn slips over the edge of the flange 19^b of the rotary tension member 19^c and then, guided by this flange, enters between the bottom 19^e of the tension member and the plate 19^a, and drops into the recess 20 in the end member 13. As the yarn is drawn down it is guided to the center of the frame by the rounded corners 79, 79' of the elements 70, 70' and the rounded corners 59, 59' of the elements 50, 50'. The yarn is drawn forward while it is drawn downward and the forward movement of the yarn pulls each of the vibratory elements backwards, permitting the yarn to be drawn between their inner edges and into the notches 57, 57' and 80. The pins 90 prevent it from being drawn below the notches. The yarn then extends through the cleaner in a straight line and is drawn forward by a winding or other machine not shown in the drawings.

In the operation of the cleaner, the vibratory elements, including both the cleaning elements 50, 50' and the cleaning and deflecting elements 70, 70', are set into vibration by the impingement against their edges of particles projecting from the yarn. As the cleaning elements 50, 50' vibrate, the cleaning edges 62, 62' of these elements strike particles projecting from the yarn and loosen or detach the particles by a brushing, scraping and "hooking" action. As the cleaning and deflecting elements 70, 70' vibrate, the edges of the notches 80 of the elements 70', and, to a less extent, the parts of the inner edges 75 of the elements 70 which are adjacent to the yarn, strike particles projecting from the yarn and detach them from the yarn by a brushing and scraping action. As the yarn is drawn through the cleaner under tension, it rotates to a certain extent while passing

through the cleaner, and as a result of this rotation all parts of its circumference are brought into contact with one or another of the notches 80 so that the yarn is cleaned throughout its circumference.

The particles which have been detached from the yarn by one of the cleaning elements 50 or one of the cleaning and deflecting elements 70, and the shreds of fiber 10 adhering to the detached particles, tend to be drawn along in the direction of the travel of the yarn. This tendency results from the air current produced by the travel of the yarn, which may be drawn through the cleaner at a rate of 1200 feet a minute. Each detached particle, with the fibrous matter adhering to it, therefore, travels along in the direction of the travel of the yarn until it strikes the inclined front surface of one of 20 the blades 73, 73'. Such of the detached particles as strike the inclined surface some little distance from the opening between the two blades, are immediately directed downwardly away from the line of travel of the 25 yarn. If, on the other hand, a detached particle happens to strike one of the blades near the opening between the blades, the shreds of fiber adhering to this particle are frequently drawn through the opening between the 30 blades by the air current. The opening between the blades is, however, so narrow that the particle itself is not drawn into this opening, but remains in contact with the front surfaces of the blades and travels down 35 along the front surfaces as the blades vibrate until it drops with its adhering fiber from the lower ends of the blades. The downward travel of the particles and fibre is facilitated by the fact that the inner edges of the 40 blades diverge from each other when the blades are turned outwardly. As a result, all the particles removed from the yarn, and all fibrous matter adhering to them, are directed downwardly within the skirt 32, and may be collected in any desired manner at or below the bottom of the skirt.

While I wish it clearly understood that my invention is by no means limited to the particular form and arrangement of parts which 50 I have described, I will nevertheless point out a number of special advantages which are obtained through the use of certain features of the embodiment of the invention which has been illustrated.

The arrangement of the cleaning elements and cleaning and deflecting elements illustrated, in which a few pairs of cleaning elements are placed so as to operate upon the 55 yarn as it enters the cleaner, and a plurality of pairs of cleaning and deflecting blades are positioned to operate upon the yarn after the cleaning elements, provides for the loosening by the cleaning elements of particles which may be firmly embedded in the yarn, before these particles are brought into con-

tact with the cleaning and deflecting elements. The arrangement has been found to effect a thorough cleaning of many different kinds of yarn and constitutes a part of my invention. It will be understood, however, 70 that the arrangement may be modified, if desired, in accordance with the character of the yarn to be cleaned and the character of the dirt which it contains. Thus, if the yarn contains many specks firmly embedded therein, it may be desirable to use more cleaning elements than are shown in the drawings. On the other hand, it has been found that some 75 yarns may be satisfactorily cleaned by the cleaning and deflecting elements alone, without the use of the cleaning elements.

The notches 80 in the cleaning and deflecting blade 73' possess two advantages. In the first place they partially surround the yarn like the notches 57 and 57' of the cleaning 80 blades 53, so that, when the blades 73' are in vibration, they have a cleaning action quite similar to that of the blades 53, 53'. In the second place, the notches 80 make it possible to place the inner edges of each pair of 85 blades 73, 73' close together without pinching the yarn. The close spacing of the blades prevents detached particles from being drawn through between the blades under the influence of the air current upon fibrous matter adhering to the particles. It is not essential, however, that only one blade of each 90 pair be notched. Thus, each deflecting blade of each pair may be notched as illustrated in Fig. 9, where the deflecting blade 73^a contains a notch 80^a, while the opposite deflecting blade 73'^a contains a similar notch 80'^a. In this case the combined depth of the 95 two notches 80^a and 80'^a is less than the diameter of the yarn, so that when the two notches contact with the yarn the inner edges 100 75^a, 75'^a of the blades are spaced apart. Consequently, where, in the claims which follow, reference is made to one of the blades having a notch in its inner edge, this should 105 be understood not to imply that the edge of the other blade must necessarily be straight. If only one blade of each pair is notched, it is not essential that all the notched blades be placed at one side of the yarn, although this arrangement has the advantage of facilitating the threading of the cleaner. It is desirable, however, that the notch or notches in 110 the inner edges of each pair of blades be so formed that they surround a portion of the circumference of the yarn when the inner edges of the blades are spaced apart from each other. The space allowed between the inner edges of the blades in their normal position is most desirably made less than the 115 diameter of the yarn, as shown; but, on the other hand, the blades should not be placed so closely that the fibrous matter detached with the particles is caught or gripped between them.

The fact that the yarn is drawn across the edges of the cleaning and deflecting blades 73, 73' some distance below the upper edges of the blades tends to prevent fibrous matter 5 removed from the yarn with the particles from catching on the tops of the blades. The positioning of the upper edges of the blades close to the bottom surface of the cover pieces tends further to prevent the collection of 10 fibrous matter on these upper edges.

Many of the features of the yarn cleaner described in this application are described and claimed in my copending application filed March 29, 1922, Serial No. 547,596, and 15 are in consequence not claimed in this application.

What is claimed is:

1. A yarn cleaner for removing particles from a traveling yarn, comprising an open 20 frame having aligned recesses in its ends to permit the passage of the yarn longitudinally across the frame, a cover on said frame, and transverse deflecting blades yieldably mounted on said frame having their inner 25 edges adjacent to the yarn and their upper edges spaced upwardly from the yarn and close to the lower surface of said cover.

2. In a yarn cleaner for removing particles from a traveling yarn, a pair of trans- 30 verse blades located on opposite sides of the yarn and having inner edges spaced by a distance less than the diameter of the yarn, one of said blades having in its inner edge a notch partially surrounding the yarn.

3. In a yarn cleaner for removing particles from a traveling yarn, a pair of blades transverse to the line of travel of the yarn and inclined thereto, located on opposite 40 sides of the yarn and having inner edges spaced by a distance less than the diameter of the yarn, one of said blades having in its inner edge an elliptically curved notch partially encircling the yarn.

4. In a yarn cleaner for removing particles from a traveling yarn, the combination of 45 means for detaching particles from the yarn, and a pair of transverse deflecting blades located on opposite sides of the yarn behind said detaching means and having inner edges spaced by a distance less than the diameter 50 of the yarn, one of the blades having in its inner edge a notch partially surrounding the yarn.

5. In a yarn cleaner for removing particles from a traveling yarn, a pair of transverse 55 blades located on opposite sides of the yarn and having inner edges spaced by a distance less than the diameter of the yarn, one of said blades having in its inner edge a notch 60 partially surrounding the yarn, and yieldable supports for said blades permitting them to vibrate freely in directions approximately longitudinal of the yarn.

6. In a yarn cleaner for removing particles 65 from a traveling yarn, a pair of blades

transverse to the line of travel of the yarn and inclined thereto, located on opposite sides of the yarn and having inner edges spaced by a distance less than the diameter of the yarn, one of said blades having in its inner edge a notch partially surrounding the 70 yarn, and yieldable supports for said blades permitting them to vibrate freely in directions approximately longitudinal of the yarn..

7. In a yarn cleaner for removing particles from a traveling yarn, a pair of blades transverse to the line of travel of the yarn and inclined thereto, located on opposite sides of the yarn and having inner edges spaced by a distance less than the diameter of the 75 yarn, one of said blades having in its inner edge a notch partially surrounding the yarn, and yieldable supports for said blades permitting a vibratory movement of their inner edges having a component longitudinal of the yarn and a component transverse to the line of travel of the yarn.

8. In a yarn cleaner for removing particles from a traveling yarn, a plurality of 90 pairs of blades transverse to the line of travel of the yarn and inclined thereto, each pair having inner edges spaced by a distance approximately equal to half the diameter of the 95 yarn and only one blade of each pair having in its inner edge a notch surrounding half the circumference of the yarn, and yieldable supports for said blades permitting free vibration thereof.

9. In a yarn cleaner for removing particles from a traveling yarn, a plurality of trans- 100 verse blades located at one side of the yarn and having straight inner edges adjacent to the yarn, a plurality of blades at the opposite side of the yarn, located, one directly 105 opposite each of said first-mentioned blades, and having in their inner edges aligned notches partially surrounding the yarn.

10. In a cleaner for removing particles from a traveling yarn, a cleaning and deflecting blade transverse to the line of travel of the yarn and inclined thereto, having an inner edge inclined to the line of travel of the 110 yarn and containing a notch partly surrounding the yarn, and a resilient support for said blade permitting a vibration of said blade in which said notch moves approximately longitudinally of the yarn.

11. In a yarn cleaner for removing particles from a traveling yarn, a pair of trans- 120 verse blades located on opposite sides of the yarn and having inner edges spaced by a distance less than the diameter of the yarn, one of said blades having in its inner edge a 125 notch partially surrounding the yarn, and supports for said blades permitting them to turn outward from each other in a direction so inclined to the blades that the lower ends of their inner edges separate more than the upper ends of said edges.

12. In a yarn cleaner for removing particles from a traveling yarn, a pair of transverse blades located on opposite sides of the yarn and having inner edges spaced by a distance less than the diameter of the yarn, one of said blades having in its inner edge a notch partially surrounding the yarn, supports for said blades permitting them to turn outward from each other in a direction so

inclined to the blades that the lower ends 10 of their inner edges separate more than the upper ends of said edges, and resilient means tending normally to position the blades in line with each other.

In testimony whereof I have hereunto set 15 my hand.

HENRY E. VAN NESS.
